Attorneys

UNITED STATES PATENT OFFICE.

FREDERICK F. COAKER, OF SHAFTESBURY, ENGLAND.

APPARATUS FOR OPENING AIR-TIGHT TINS.

1,376,515.

Specification of Letters Patent.

Patented May 3, 1921.

Application filed July 7, 1920. Serial No. 394,599.

To all whom it may concern:

Be it known that I, FREDERICK FRANK COAKER, a subject of the King of Great Britain and Ireland, residing at 25 High street, Shaftesbury, in the county of Dorset, England, have invented a new and useful Improvement in Apparatus for Opening Air-Tight Tins, of which the following is a specification.

10 My invention relates to an improved construction of airtight sealed tins provided with a slip-on lid having attached to it two cutters adapted to come into operation and cut through the airtight lid when it is desired 15 to open the tin; the slip-on lid provided with a hinge remaining as the lid of the tin when the same has been opened.

I have illustrated my invention in the accompanying drawing in which—

20 Figure 1. shows a plan view of the airtight sealed top of a rectangular tin according to my invention.

Fig. 2. shows a view of the entire construction in isometric perspective.

25 Fig. 3. is a section of a portion of the tin, showing the hinged slip-on lid in place on the airtight closed tin.

Fig. 4 is a section showing the cutter in 30 position, while the airtight closure is intact.

Fig. 5. is a section showing the piercing cutter pressed into position through the sealed lid.

Fig. 6. shows the cutter in operative position and the hinged side piece of the slip-on cover raised.

My apparatus consists of a square slip-on cover 1, with three fixed sides or flanges 2, the fourth side 3 being hinged. Attached 40 to this cover are two cutters 4 each having a sloping cutting edge and a vertical back. The cutters are arranged so that they remain wedged between the sides of the cover and the sides of the tin until required for the 45 purpose of opening the tin 6, when the cover is removed from the tin and each cutter is slid slightly inward, into such a position as

to drop just within the sides of the tin. The cover is then replaced on the tin, and forced down, the two cutters puncturing the 50 sealed top of the tin. The cover is then slid across the tin away from its hinged side the two cutters meantime making two incisions the whole width of the tin. The cover is then again removed and replaced 55 so as to travel in a direction at right angles to the direction previously traveled and the same operation repeated, resulting in two further incisions throughout the whole width of the tin. The result is that the airtight lid 5 of the tin 6 is completely cut around and can be removed. The slip-on cover can then be replaced and used as an ordinary cover to the tin. For the purpose 60 of holding the hinged portion of the cover in position when used merely as a cover, the hinged portion is provided with a small flap 7 at each end which comes into contact with the adjacent side of the cover and is held in position by a slight protuberance 65 80 corresponding with a slight hollow in the side of the tin.

What I claim is:—

1. In combination, a rectangular airtight closed tin, a slip-on cover fitting on the top 75 of said tin, a hinged side piece on said cover and a pair of cutters on said cover capable of being pressed downward to pierce through the airtight lid of the tin and slit the same when the slip-on cover is drawn 80 across the lid.

2. In the apparatus claimed in claim 1, the feature that the cutters are located between the outside of the tin and the hinged 85 flange of the slip-on cover until the said cover is replaced in the cutting position upon the tin lid.

3. In the apparatus claimed in claims 1 and 2, a recurved attachment 7 at each end 90 of the hinged cover-flange.

In testimony whereof I have signed my name to this specification.

F. F. COAKER.
